UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed March 19, 1930. Serial No. 437,233.

This invention relates to improvements in mining machines and more particularly has reference to improved flexible feeding means for a coal mining machine of the continuous cutter, bottom cutting type.

An object of this invention is to provide an improved mining machine feeding means and more particularly improved flexible feeding means for a coal mining machine of the room and pillar type. Another object is to provide an improved flexible feeding means for a room and pillar type mining machine whereby the machine is fed and guided in an improved and more flexible manner. A further object is to provide an improved feeding means of the aforesaid character wherein the relatively rotatable feed operating and controlling members and the driving means therefor are arranged in an improved manner on the machine whereby an extremely compact feeding mechanism may be had, the feed operating and controlling members being arranged on angularly disposed axes extending at oblique angles from the central longitudinal vertical plane of the machine. These and other objects and advantages of this invention will, however, hereinafter more fully appear.

In the accompanying drawings there is shown for purposes of illustration one form which the invention may assume in practice.

In these drawings,—

Fig. 1 is a plan view of the illustrative embodiment of the improved mining machine.

Fig. 2 is an enlarged side elevational view of the feeding end of the machine shown in Fig. 1.

Fig. 3 is a rear elevational view of the machine shown in Figs. 1 and 2.

Fig. 4 is an enlarged horizontal sectional view illustrating the structural details of the improved feeding mechanism.

Fig. 5 is a central longitudinally extending vertical sectional view taken substantially on line 5—5 of Fig. 4.

Fig. 6 is a detail sectional view taken on line 6—6 of Fig. 5.

In this illustrative embodiment of the invention the improved feeding means is shown

embodied in a coal mining machine of the continuous cutter, bottom cutting, room and pillar type, although it is evident that the various novel features of the improved feeding means may be incorporated in coal mining machines of various other types. The mining machine generally comprises a low compact machine frame or body 1 having a smooth plane bottom surface 2 upon which the machine is slidably supported for movement over the mine bottom. Secured rigidly within the machine frame and projecting forwardly lengthwise thereof is a plane cutter bar 3 supporting on its margin an endless cutter bit carrying cutter chain 4. Arranged in a novel manner as hereinafter described on the rear end of the machine frame are relatively rotatable feed operating and controlling members 5 and 6, herein in the form of cable winding or haulage drums, cooperating with flexible feeding and controlling cables 7 and 8 respectively. As shown in Figs. 1 and 3, arranged in a novel manner on vertical axes at the rear end of the machine frame adjacent the feed and controlling drums are guide sheaves 9, 10, 11 and 12, while arranged at the opposite sides of the front end of the machine frame are guide sheaves 13 and 14 and these guide sheaves are adapted to guide the feed and controlling cables during the various operations of the machine in a manner well understood in the mining machine art. Carried centrally by the machine frame is a low compact motor 15, herein preferably of the reversible electric type, having its power shaft 16 horizontally disposed and extending longitudinally of the machine. The cutter chain 4 is operatively connected to the front end of the motor shaft through any approved transmission mechanism, which may be of the same general type as that disclosed in my copending application Ser. No. 179,357, filed March 29, 1927. The feed and controlling drums 5 and 6 are driven from the rear end of the motor shaft 16 through improved transmission connections to be now described.

Now referring to the improved feeding means and more particularly to the improved driving means therefor, it will be noted that

secured to the rear end of the motor shaft 16 is a spur pinion 17 meshing with a spur gear 18 (see Fig. 6) in turn meshing with a spur gear 19 keyed to the front end of a horizontal shaft 20. The shaft 20 extends longitudinally of the machine and is suitably journaled within the lower part of the feed frame section. As shown in Figs. 4 and 5, keyed to the shaft 20 intermediate its ends 10 is a worm 21 having meshing therewith at its opposite sides worm wheels 22 and 23 rotating on parallel vertical axes at the opposite sides of the central longitudinal median line of the machine. These worm wheels are 15 keyed to vertical shafts 24 and 25 respectively suitably journaled within the feed frame section and having fixed thereto worms 26 and 27 respectively. Meshing with the worm 26 is a slow speed worm wheel 28, while a 20 similar slow speed worm wheel 29 meshes with the worm 27. As shown, these worm wheels are arranged coaxially with horizontal shafts 30 and 31 respectively, suitably journaled within the machine frame. These 25 shafts are arranged on angularly disposed axes extending at oblique angles from the central longitudinal vertical plane of the machine. The worm wheels 28 and 29 are connectible with their respective shafts by multiple disc clutches 32 and 33 respectively. Keyed to the outer ends of the shafts 30 and 31 are gears 34 and 35 respectively meshing with the teeth of internal gears 36 and 37 herein formed integral with the haulage 30 drums 5 and 6. It will thus be seen that when the clutch 32 is applied the feed drum 5 may be driven in winding direction at a relatively slow speed appropriate for cutting, through gearing 17, 18, 19, shaft 20, 40 worm gearing 21, 22, 26, 28, shaft 30 and gear 34 meshing with the internal gear 36 secured to the drum. Also when the clutch 33 is applied the winding drum 6 may be driven in winding direction at a similar 45 speed through a similar train of gearing.

Now referring to the fast speed driving means for the feed and controlling drums, it will be noted that keyed also to the shaft 20 is a worm 38 having meshing therewith at its 50 opposite sides worm wheels 39 and 40 rotating on parallel vertical axes at the opposite sides of the central longitudinal vertical plane of the machine. These worm wheels are keyed to vertical shafts 41 and 42 respectively, suitably journaled within the feed frame section and these shafts have fixed thereto worms 43 and 44 meshing with fast speed worm wheels 45 and 46 respectively, 55 rotatably supported on the angularly disposed shafts 30 and 31 in coaxial relation with the worm wheels 28 and 29. These worm wheels 45 and 46 are connectible with the shafts 30 and 31 by means of multiple disc clutches 47 and 48 respectively. It will 60 thus be seen that when the friction clutch 47

is applied, the feed drum 5 may be driven in winding direction at a relatively fast "haulage" speed through spur gearing 17, 18, 19, shaft 20, worm gearing 38, 39, 43, 45, shaft 30 and gear 34 meshing with the internal gear 36 secured to the drum. Also when the friction clutch 48 is applied, the controlling drum 6 may be driven in winding direction at a similar speed through a similar gear train. It will also be noted that the drums 5 and 6 may be driven in winding direction either separately or simultaneously at relatively high speed or at relatively low speed and that upon partial release of the friction clutches the drums may rotate in unwinding direction under various degrees of frictional resistance. When the friction clutches are entirely released, the drums may freely rotate.

The operating mechanism for the several friction controlling clutches will now be described. Encircling each of the shafts 30, 31 are cylindrical pressure plates 50 and 51 having projecting fingers extending through apertures formed in the end plates of the clutch housing and worm wheel respectively. Interposed between these pressure plates for each of the sets of friction clutches are pivoted shipper yokes 52 and 53 respectively, each having an operating handle, 54 and 55, conveniently located at the top of the machine. It will thus be seen that the parts are so arranged that only one clutch of one set may be applied at one time.

As mentioned above, the feed and controlling drums 5 and 6 are arranged on angularly disposed axes extending at oblique angles from the central longitudinal vertical plane of the machine and in the present instance are arranged on the opposite sides of the rear end of the feed frame section. Each of these drums is rotatably supported on horizontal stub shafts 56 and 57 projecting laterally from plates 58 detachably secured to the converging vertical side walls of the feed frame section. These stub shafts support anti-friction bearings on which the drums are rotatably mounted and the drums are each composed of two parts secured together to form an internal chamber 59 within which the bearing structure is enclosed. Various modes of operation of the improved feeding means will be clearly apparent to those skilled in the mining machine art, and as the method of use of a room and pillar mining machine is well known, a description of the general mode of operation of the machine is thought unnecessary.

As a result of this invention it will be noted that an improved flexible feeding means is provided for a coal mining machine of the continuous cutter, bottom cutting type whereby the machine is fed and guided in a more efficient and advantageous manner. It will further be noted that by arranging

the feed and controlling drums on angularly disposed axes extending at oblique angles from the central longitudinal vertical plane of the machine, the feeding mechanism is rendered extremely compact both laterally and vertically. It will further be noted that by providing the improved driving and controlling means for the feed and controlling drums it is possible to effect rotation of the drums in winding direction by power either separately or simultaneously at relatively low speed or at relatively high speed, or to permit rotation of the drum in unwinding direction under various degrees of frictional resistance or without such resistance, thereby rendering the machine well adapted to accommodate itself to the various mining conditions encountered in room and pillar work. These and other advantages of the improved feeding means will be clearly apparent to those skilled in this art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mining machine feeding mechanism including relatively rotatable feed members each adapted to cooperate directly with flexible feeding means and disposed on axes at oblique angles to the central longitudinal median line of the machine.

2. A mining machine feeding mechanism including relatively rotatable feed members each adapted to cooperate directly with flexible feeding means and disposed at the opposite sides of the rear end of the machine with their axes at substantially right angles, one of said members lying within a transverse zone bounded by parallel transverse vertical planes perpendicular to the central longitudinal vertical plane of the machine and respectively including the foremost and rearmost points on said other member.

3. A mining machine feeding mechanism including relatively rotatable feed members each adapted to cooperate directly with flexible feeding means and disposed at the rear end of the machine with their axes horizontal and at substantially right angles, one of said members lying within a transverse zone bounded by parallel transverse vertical planes perpendicular to the central longitudinal vertical plane of the machine and respectively including the foremost and rearmost points on said other member.

4. A mining machine feeding mechanism including relatively rotatable feed members each adapted to cooperate directly with flexible feeding means and disposed with their

axes horizontal and at oblique angles to the central longitudinal median line of the machine.

5. A mining machine feeding mechanism including a rotatable feed operating member adapted to cooperate directly with flexible feeding means and disposed with its axis horizontal and at a substantially oblique angle to the central longitudinal median line of the machine with its axial line sloping forwardly as it approaches said median line.

6. A mining machine feeding mechanism including relatively rotatable feed members each adapted to cooperate directly with flexible feeding means and disposed at the rear end of the machine with their axes horizontal and at substantially oblique angles to and at opposite sides of the central longitudinal vertical plane of the machine.

7. A mining machine feeding mechanism including relatively rotatable feed operating and controlling members each adapted to cooperate directly with flexible feeding means and disposed at the rear end of the machine with their axes at substantially right angles, one of said members lying within a transverse zone bounded by parallel transverse vertical planes perpendicular to the central longitudinal vertical plane of the machine and respectively including the foremost and rearmost points on said other member, and motor operated driving means for said members.

8. A mining machine feeding mechanism including relatively rotatable feed operating and controlling members each adapted to cooperate directly with flexible feeding means and disposed on axes at oblique angles to the central longitudinal median line of the machine, and motor operated driving means for said members.

9. A mining machine feeding mechanism including relatively rotatable feed operating and controlling members each adapted to cooperate directly with flexible feeding means and disposed at the rear end of the machine at opposite sides of the central longitudinal median line of the latter and with their axes at substantially right angles, one of said members lying within a transverse zone bounded by parallel transverse vertical plane perpendicular to the central longitudinal vertical plane of the machine and respectively including the foremost and rearmost points on said other member, and motor operated driving means for said members.

10. A mining machine feeding mechanism including relatively rotatable feed operating and controlling members each adapted to cooperate directly with flexible feeding means and disposed at the rear end of the machine with their axes horizontal and at substantially right angles, one of said members lying within a transverse zone bounded by parallel transverse vertical planes perpendicular to the central longitudinal vertical plane of the

- machine and respectively including the foremost and rearmost points on said other member, and motor operated driving means for said members.
11. A mining machine feeding mechanism including relatively rotatable feed operating and controlling members each adapted to cooperate directly with flexible feeding means and disposed with their axes horizontal and 10 at oblique angles to the central longitudinal median line of the machine, and motor operated driving means for said members.
12. A mining machine feeding mechanism including a rotatable feed operating member 15 adapted to cooperate directly with flexible feeding means and disposed with its axis horizontal and at a substantially oblique angle to the central longitudinal median line of the machine with its axial line sloping forwardly as it approaches said median line, and motor operated driving means for said member.
13. A mining machine feeding mechanism including relatively rotatable feed members 20 each adapted to cooperate directly with flexible feeding means and disposed within the lateral limits of the machine on axes at oblique angles to the central longitudinal median line of the machine.
14. A mining machine feeding mechanism 25 including relatively rotatable feed members each adapted to cooperate directly with flexible feeding means and disposed within the lateral limits of the machine at the rear end of the machine with their axes at substantially right angles.
15. A mining machine feeding mechanism including relatively rotatable feed operating and controlling members each adapted to cooperate directly with flexible feeding means 30 and disposed at the same end of the machine with their axes horizontal and at substantially right angles, one of said members lying within a transverse zone bounded by parallel transverse vertical planes perpendicular to the central longitudinal vertical plane of the machine and respectively including the foremost and rearmost points on said other member, and motor operated driving means for said members.
16. A mining machine feeding mechanism including relatively rotatable feed operating and controlling members each adapted to cooperate directly with flexible feeding means and disposed at the same end of the machine 35 at opposite sides of the central longitudinal median line of the latter and with their axes at substantially right angles, one of said members lying within a transverse zone bounded by parallel transverse vertical planes perpendicular to the central longitudinal vertical plane of the machine and respectively including the foremost and rearmost points on said other member, and motor operated driving means for said members.
17. A mining machine feeding mechanism 40 including relatively rotatable feed operating and controlling members each adapted to cooperate directly with flexible feeding means and disposed in symmetrical relation at the opposite sides of the same end of the machine with their axes horizontal and at substantially right angles, and motor operated driving means for said members.
18. A mining machine feeding mechanism including relatively rotatable feed members 45 each adapted to cooperate directly with flexible feeding means and disposed in the same transverse zone within the lateral limits of the machine at the same end of the machine with their axes at substantially right angles.
19. A mining machine feeding mechanism including a rotatable feed operating member adapted to cooperate directly with flexible feeding means, said member rotating on a horizontal axis in a line whose portion between the feed operating member and the central longitudinal vertical plane of the machine makes an acute angle with the portion of said plane lying to the rear of the point of intersection of said line with said plane.
20. A mining machine feeding mechanism 50 including a machine frame, and a rotatable feed operating member thereon adapted to cooperate directly with flexible feeding means and disposed wholly within the lateral limits of said frame with its axis horizontal and at a substantial oblique angle to the central longitudinal median line of the machine.
21. A mining machine feeding mechanism 55 including relatively rotatable feed members each adapted to cooperate directly with flexible feeding means and disposed on axes at oblique angles to the central longitudinal median line of the machine, and motor operated driving means for said members including shafts one operatively connected to each feed member and arranged on axes extending in the same direction as said feed member axes.
22. A mining machine feeding mechanism 60 including relatively rotatable feed members each adapted to cooperate directly with flexible feeding means and disposed on axes at oblique angles to the central longitudinal median line of the machine, and motor operated driving means for said members including shafts one operatively connected to each feed member and arranged on axes extending in the same direction as said feed member axes, and a shaft extending longitudinally of the machine at the longitudinal vertical center thereof and operatively connected to said shafts.
23. A mining machine feeding mechanism 65 including relatively rotatable feed members each adapted to cooperate directly with flexible feeding means and disposed on axes at oblique angles to the central longitudinal median line of the machine, and motor oper-

ated driving means for said members including shafts one operatively connected to each feed member and arranged on axes extending in the same direction as said feed member
5 axes, a shaft extending longitudinally of the machine at the longitudinal vertical center thereof, and plural speed driving connections between said longitudinally extending shaft and said angularly disposed shafts.

10 In testimony whereof I affix my signature.
MORRIS P. HOLMES.
